(57) **CLAIM**

The ornamental design for a kitchen utensil for food retort pouches, as shown and described.

DESCRIPTION

FIG. 1 is a perspective view of an outer member of a kitchen utensil for food retort pouches, showing my new design; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view taken along the line 8-8 of FIG. 6;

FIG. 9 is a perspective view of an inner member of the kitchen utensil for food retort pouches;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a perspective view of the kitchen utensil for food retort pouches, in which the inner member and the outer member are shown assembled.
